SVEN WIGELIUS, OF STOCKHOLM, SWEDEN, ASSIGNOR TO AKTIEBOLAGET WIGELIUS MOTOREER, OF STOCKHOLM, SWEDEN.

FUEL-INJECTOR.

1,112,878.

Specification of Letters Patent.

Patented Oct. 6, 1914.

Application filed April 26, 1910. Serial No. 557,783.

To all whom it may concern:

Be it known that I, SVEN WIGELIUS, a subject of the King of Sweden, residing at Kapteusgatan 17, Stockholm, Sweden, have 5 invented new and useful Improvements in Fuel-Injectors, of which the following is a specification.

The object of the present invention is a fuel injector for regulating the mixture of 10 air and fuel and for regulating the quantity of air introduced into the cylinder.

The object of the present invention is to provide a fuel injector in which an annular valve consisting of a movable sleeve forms 15 part of the air channel which communicates with the combustion chamber during the open position of the valve which construction differs from the known constructions of this kind by providing the movable sleeve 20 partly limiting the air inlet channel with two oppositely arranged valve faces which form valves with two conveniently arranged fixed valve faces.

The object of the invention is chiefly used 25 in connection with fuel injectors in which a regulating spindle is arranged with the air inlet channel.

The drawing shows one embodiment of the invention in longitudinal section.

30 The outer sleeve *a* is adapted to receive a threaded plug *b* secured into the same and *c* designates a tubular sleeve adapted to execute a slight up and down movement. *d* is a regulating spindle provided with a regulating device *e* and forming with the inner walls of the plug *b* and the sleeves *c* an air 35 inlet channel the cross-sectional area of which is changing upon the operation of the spindle *d*. The lower end of the sleeve *c* 40 and the upper end of the plug *b* are shaped so as to form a valve *g*. By the positive operation of the sleeve *c* the valve *g* is alternately opened and closed, and the annular space *h* is alternately in communication 45 with the channel *f* or closed against the same.

In order to obtain a perfect mixture of air and fuel, the mouth of the valve *g* is arranged in close proximity to a contraction 50 of the channel *f* thereby greatly increasing the velocity of the air when passing this place in order to make the mixture a perfect and most intimate one. If the fuel is introduced by a special mechanical device, two 55 valves must be arranged one of which is

regulating the flow of the fuel between a receptacle and a pump and the other the flow between a pump and air channel. For this purpose the sleeve *c* is provided with a second valve *k* arranged between the annular space *h* and another annular space *i* which latter is connected with a fuel container by means of the channel *m*. The sleeve *c* executes only an extremely limited movement in the direction of its longitudinal axis by which alternately the valves *g* and *k* are opened or closed. If the sleeve is in its lower position, the valve *k* is open and the valve *g* closed. In this position the fuel, by virtue of the suction of the pump communicating with the channel *i* is pumped from *m* through *h*, and *i* into the pump chamber, if then the sleeve is moved into its upper position, the fuel is pressed by the pump through *i*, *h* and *g* into the channel *f*. The fuel, however, cannot be pressed back into the receptacle because the valve *k* is now closed.

It is clear, that the pump communicating with the space *i* must execute a positively regulated movement relatively to the sleeve *c* and spindle *d*. By the above described construction, the annular space *h* and also the pump connected with the space *i* will be alternately brought in communication 85 upon the suction stroke of the pump with the fuel receptacle and upon its pressure stroke with the air inlet channel *f*.

It will be evident, that the injection of the fuel must commence and cease at the moment or nearly in the moment in which the current of air through the channel *f* is started or ceases. This is effected by the arrangement of the spindle *d* and the sleeve *c* in such a manner that they begin their movement in each direction simultaneously. The sleeve *c* however, executes a considerable shorter movement than the spindle and therefore it will stop in each direction before the spindle stops. This combined movement is obtained in a very simple manner by positively regulating the movement of the spindle *d* for instance by means of a cam disk, crank or the like, and by the frictional engagement between the sleeve *c* and the spindle or a part connected therewith, by which the sleeve is carried along. The operation of the sleeves is limited by the upper and lower fixed valve faces. The spindle *d* however can execute a movement inde-

pendent from the sleeve d . If the spindle d is stationary the parts surrounding the same must be movable. It is clear that the object of the present invention may equally well be used with any regulating device for combustion engines in which the fuel is at times admitted into the air inlet channel in order to be mixed with air.

What I claim is:

- 10 In a fuel injector of the character described, the combination of an outer sleeve and a plug screwed into the same from below with a movable sleeve, an air inlet channel formed by the inner walls of said plug 15 and the movable sleeve for supplying air,

said movable sleeve limiting the cross-sectional area of said inlet channel, valve faces upon opposite sides of said sleeve and valve faces upon said plug and upon said outer sleeve for forming valves with the valve 20 faces of said movable sleeve constituting a means for supplying fuel.

In testimony whereof I have signed my name to this specification in the presence of two subscribing witnesses.

SVEN WIGELIUS.
